UNITED STATES PATENT OFFICE.

JOHN H. TALGE, OF INDIANAPOLIS, INDIANA.

VENEER-CLAMP.

No. 858,921.

Specification of Letters Patent.

Patented July 2, 1907.

Application filed March 7, 1907. Serial No. 361,103.

To all whom it may concern:

Be it known that I, JOHN H. TALGE, a citizen of the United States, residing at Indianapolis, in the county of Marion and State of Indiana, have invented certain new and useful Improvements in Veneer-Clamps, of which the following is a specification.

The object of my invention is to produce a simple yet efficient means by which two veneers may be brought together edge to edge and connected.

10 The accompanying drawings illustrate my invention:

Figure 1 is a side elevation; Fig. 2 a plan; Fig. 3 a bottom view; Fig. 4 a vertical section showing a roll of prepared jointing tape conveniently mounted; Fig. 5 a sectional detail showing the means for supporting and controlling the adjustable member; Fig. 6 a similar detail of the non-adjustable member, and Fig. 7 a perspective view of a convenient iron for quickly drying a prepared jointing tape.

20 In the drawings 10 indicates a main work table supported in any suitable manner, as by means of legs 11; the upper face of said table being true and smooth. Mounted upon the upper face of the table 10 to one side of its middle, is a clamping bar 12 provided at each end with a pin 13 which extends down through table 10. For convenience of adjustment I thread the upper end of each pin 13 and provide the bar 12 with a threaded thimble 14, the arrangement being such that pin 13 may be vertically adjusted in bar 20 and held in any desired adjustment by a check nut. 30 Each pin 13 is pivoted at its lower end to one arm of a bell-crank lever 16 pivoted on the lower side of the table 10. The opposite arms of lever 16 are connected by links 17 to opposite sides of a rocking head 18 pivoted on a pin 19 on the under side of table 10, the arrangement being such that, by shifting head 18, the two levers 16 may be simultaneously swung and the bar 12 raised from or lowered toward the table 10.

Passing through table 10 adjacent each pin 13 is a 40 similar pin 20, threaded at its upper end to receive a nut 21, and at its upper end pivoted to one arm of a lever 22 like lever 16. The opposite arms of lever 22 are connected by links 23 with a head 24 pivoted on pin 19, and the two heads 18 and 24 are provided with 45 convenient handles 18' and 24' respectively. Threaded upon the upper end of each pin 20 beneath nut 21 is a thimble 25.

Mounted on the two thimbles 25, 25 is a clamping bar 26 similar to the bar 12 but provided on its lower 50 face with a rough material, such as sand paper 27. Bar 26 has a limited transverse play on each thimble 25 (the hole 26' being a little larger than the stem of

the thimble) and provided upon each thimble is a lever 30. The short arm of lever 30 is pivoted, at 31, to bar 26 while the long arms are extended toward 55 each other to near the middle of the machine.

If prepared jointing tape is to be used, a roll 40 of such tape may be journaled at one end of the apparatus on a bracket 41.

In operation; the two levers 18' and 24' are thrown 60 apart so as to lift the bars 12 and 26 up away from table 10. Two strips of veneer, having been previously prepared at their edges, are thus slipped beneath the clamps, as indicated in dotted lines in Fig. 2, the adjacent edges being brought approximately into engagement. Levers 18' and 24' are then brought together so as to clamp the veneers down upon the table. The operator then grasps levers 30 and, by swinging these levers independently the bar 26 may be transversely shifted relative to bar 12 and, because 65 of its roughened under surface and the smooth surface of table 10, the veneer beneath this bar will be shifted relative to the other veneer until the two edges of the veneers are brought into contact throughout their entire length. Thereupon the edges are secured together in any desired manner. For instance, the prepared tape 40 is applied and quickly dried by a heated iron 50, or in any desired manner. The levers 18' and 24' are then separated, the connected 70 veneers withdrawn, and the operation repeated. 80

I claim as my invention:

1. In a veneer clamp, the combination, with a support, of a pair of clamping bars thereon, means for raising and lowering said bars, and means for independently shifting one of said bars relative to the other both transversely and angularly. 85

2. In a veneer clamp, the combination, with a support, of a pair of clamping bars thereon, means for independently raising and lowering said bars, and means for independently shifting one of said bars relative to the other 90 transversely and angularly.

3. In a veneer clamp, the combination, with a supporting table, of a pair of clamping bars thereon, a pair of pins carried by each of said bars and projecting downward through the table, means engaging one pair of pins for shifting the same simultaneously through the table, independent means engaging the other pair of pins for shifting the same simultaneously through the table, and means for shifting one of said bars transversely on its pins. 95

4. In a veneer clamp, the combination, with a supporting table, of a pair of clamping bars thereon, a pair of pins carried by each of said bars and projecting downward through the table, means engaging one pair of pins for shifting the same simultaneously through the table, independent means engaging the other pair of pins for shifting the same simultaneously through the table, a pair of levers each pivoted on one of said last mentioned pins and connected with the clamping bar carried thereon, whereby said bar may be shifted transversely on its pins. 100

5. In a veneer clamp, the combination, with a supporting table, of a pair of clamping bars thereon, a pair of pins carried by each of said bars and projecting downward through the table, a bell-crank lever supporting each of said pins, a pair of links connected with the said levers of one clamping bar, a rocking head connecting said links, and second pair of links connected to the levers of the other clamping bar, a second rocking head connecting said last-mentioned links, and a pair of levers pivoted upon the pins of one clamping bar and connected to said clamping

bar, whereby said bar may be shifted transversely relative to the other clamping bar.

In witness whereof, I, have hereunto set my hand and seal at Indianapolis, Indiana, this sixteenth day of February, A. D. one thousand nine hundred and seven.

JOHN H. TALGE. [L. S.]
